ELECTRICAL DISCHARGE APPARATUS

Charles E. Strecker, deceased, late of Danville, Ill., by
Jeanne E. Strecker, executrix, Danville, Ill., assignor to
General Electric Company, a corporation of New York

Filed May 27, 1959, Ser. No. 816,341

6 Claims. (Cl. 315—100)

This invention relates generally to circuits and apparatus for starting and operating gaseous electric discharge lamps from an alternating current source, and more particularly to such circuits and apparatus for use with hot cathode fluorescent lamps.

Some forms of electric lamps presently available employ two thermionic cathodes, one at each end of the fluorescent lamp respectively, which may be characterized in that the cathodes are continuously heated to electron emission temperatures at voltages below the ionization voltage of the gas or vapor in the lamp. One such lamp is the so-called rapid-start type lamp as described in U.S. Patent 2,774,918 issued December 18, 1956 to Eugene Lemmers, and assigned to the same assignee as the instant application.

Two or more heated cathode discharge lamps are frequently connected in series with a ballast across a relatively high voltage supply source, but of insufficient voltage to start either lamp; for example, across a 460 volt source available for industrial distribution. As is well-known, normal residential and commercial distribution voltage is in the range from 110 to 240 volts; industrial voltages are generally distributed at 220 to 480 volts. The circuit apparatus for two such serially connected lamps normally includes a cathode heating transformer for supplying heating current to the lamp cathodes, a starting capacitor for starting first one and then the other of such discharge lamps, a power correcting capacitive reactor for improving input power factor, and an inductive ballasting impedance which limits the current flow through the discharge lamps during operation, and which is required due to the negative current characteristic of the lamp.

In such apparatus, it has been common practice to connect the primary winding of the cathode heating transformer directly across the supply line or across the lamps. This has resulted in a transformer having a low current, high voltage primary requiring a primary winding of very fine wire and which is, in general, expensive to manufacture. In order to reduce the cost of the apparatus, it would be desirable if a cathode heating transformer could be used having a low voltage, high current primary.

Certain improved apparatus described and claimed in an application filed by Wesley W. Brooks and me on even date herewith, entitled "Electric Discharge Apparatus," and assigned to the same assignee as the present invention, overcomes the aforementioned difficulties for a lighting system for connection to a high voltage source of sufficient voltage to start and operate the lamps, such as a 550 volt source. However, the aforementioned invention is not adapted for use where the source of high voltage is insufficient to start the lamps. The instant invention is an improvement over the invention described in the aforesaid Brooks et al. co-pending application and has as its object the provision of an improved apparatus having especially good lamp current regulation suitable for operating at least one discharge lamp from a source of high voltage insufficient to start the lamp.

2

Another object of this invention is to provide an improved electrical circuit and apparatus for starting and operating electric discharge lamps where the cathode heating transformer is connected for energization at a relatively low voltage and which results in particularly good lamp current regulation.

Another object is the provision of an improved electrical circuit and apparatus for operating a pair of serially connected discharge lamps from a source of high voltage insufficient to start either lamp.

Briefly stated, according to the present invention, the improved electrical circuit and apparatus for starting and operating at least one discharge lamp comprises a cathode heating transformer having a primary winding in series circuit relation with a capacitive reactor across a high voltage supply source of insufficient voltage to start the lamp. The capacitive reactor has sufficient capacitance with reference to the inductance of the transformer to draw a leading current through the transformer primary. As is well-known, a leading current through an inductance causes a voltage rise in the inductance. A starting and operating loop includes the transformer primary and the lamp in a series circuit across the source of alternating current. The rise in voltage across the inductance creates a voltage across the lamp greater than the source voltage. This increased voltage is sufficient to start the lamp.

The invention, together with additional objects and advantages thereof, will be best understood from the following description of specific embodiments, read in connection with the accompanying drawing, in which:

Fig. 1 is a schematic diagram of an improved discharge circuit and apparatus according to the invention; and

Fig. 2 is a schematic diagram of an improved discharge circuit and apparatus illustrating another embodiment of the invention.

Referring to the modification of Fig. 1, the improved ballast transformer apparatus 1 includes a low voltage cathode heating transformer 2 having a primary winding 3 and secondary cathode heating windings 4, 5, and 6 on a magnetic core 7. A pair of leads 8, 9 extend from the ballast transformer apparatus 1 for connection across a source of alternating current voltage 10, 11. One lead 8 is connected to a first end of the primary winding 3. The other end of the primary winding 3 is connected by means of line 12 to one end of a current limiting inductive reactor 13. The junction 14 at the second end of the primary winding 3 and the ballasting winding 13 is connected to a capacitive reactor 15; the other end of the capacitive reactor 15 is connected to lead 9.

The ballast transformer apparatus 1 is connected to operate a pair of serially connected lamps 16, 17. Each lamp has a heated cathode in its respective end; lamp 16 has cathodes 18 and 19 in the ends thereof; lamp 17 has cathodes 20 and 21 in the ends thereof. Leads 22, 23 extend from the first secondary cathode heating winding 4 for connection to cathode 19 of lamp 16 and to cathode 20 of lamp 17. Cathode heating winding 5 has a pair of leads 24, 25 for connection to cathode 18 of lamp 16. Cathode heating winding 6 has a pair of leads 26, 27, which, in conjunction with lead 9, connect cathode heating winding 6 across cathode 21 of lamp 17. Connected across the second lamp 17 is a low capacitance starting capacitor 28 in parallel with the second lamp 17.

The reactance of capacitive reactor 15 is selected in magnitude with respect to the inductance reactance of transformer 2 so that when no current is flowing through lamps 16 and 17, the capacitive reactance of capacitive reactor 15 is such with respect to the inductive reactance of transformer 2 that a leading current will flow in a series circuit across the source 10, 11 of alternating current voltage including the primary 3 of the transformer 2 and the capacitive reactor 15. The source 10, 11 of alternating

current voltage is, as heretofore described, of insufficient voltage to start the lamps 16, 17. However, as is well-known, when a leading current is drawn through an inductance, the voltage appearing across the inductance will generally be additive to the supply voltage. Therefore, as the capacitive reactor 15 is sufficient to draw a leading current through the transformer 2, the voltage appearing across the primary winding 3 will have sufficient magnitude to start the lamps in sequence as hereinafter explained.

In a conventionally installed rapid-start lamp system, the lamps 16, 17 are in close proximity to, and therefore in capacitive relation to, a conducting part here shown as fixture 29. As a starting aid, the fixture 29 is in electrical circuit relation to the low potential side 11 of the supply source 10, 11. Since normal residential and commercial electrical distribution systems in this country have their low potential side grounded, as shown by ground 30, the fixture 29 may be an electrical circuit with the low potential side 11 of the supply source 10, 11 through grounds 30 and 31.

Prior to starting of the lamps 16, 17, when the circuit is first energized, neither lamp is conducting. However, a small amount of current will be drawn in the series circuit including the transformer primary 3 and the capacitive reactor 15 thereby creating an increase in voltage as explained above. A first series starting circuit or loop will include the primary 3, the current limiting reactor 13, the first lamp 16, and the starting capacitor 28, connected in a series circuit across the source 10, 11 of alternating current voltage. Since no operating current is flowing in the circuit, there is no significant voltage drop across the starting capacitor 28, and the increased voltage across the primary winding 3 is sufficient to start lamp 16. Once lamp 16 has started, the voltage will be placed across the second lamp 17 in a second starting loop including the primary winding 3 of the cathode heating transformer, the current limiting reactor 13, the first lamp 16 (which has now started), and the second lamp 17, in a series circuit across the source 10, 11 of alternating current voltage. The voltage across lamp 17 is adequate to start the lamp and lamp 17 now starts. The operating current across the electrodes of the lamps is large with respect to the current flow through the starting capacitor 28; the current flow through the starting capacitor will be minor with reference to the operating circuit. The impedance of current limiting reactor 13 is sufficient to ballast the lamps and to limit the operating voltage drop across the primary winding 3 to a relatively value, thereby obtaining the benefits described above.

In a typical circuit according to the modification of Fig. 1, the lamps 16, 17 may each be a 0.8 ampere lamp, General Electric Company Catalogue No. 96T12; the supply voltage may consist of a 460 volt, 60 cycle distribution system. The current limiting reactor 13 may have an inductive impedance of 1.0 henries to limit the current flow through the lamps, after starting, to 0.8 R.M.S. amperes, and to restrict the voltage drop across the primary 3 of the cathode heating transformer 2 to 66 volts. A 3.9 mfd. capacitive reactor 15 will produce the desired power factor correction and current phase. The starting capacitor 28 may have value of 0.075 mfd. The cathode heating transformer 2 is arranged with the proper turns ratio so that 3.5 volts potential is supplied to each cathode. The above described circuit, according to the instant invention, will consume approximately 305 volt-amperes in reactor 13, 44 volt-amperes in the cathode heating transformer 2; and 550 volt-amperes in capacitive reactor 15.

The modification of Fig. 2 is similar to that illustrated in Fig. 1, except the cathode heating transformer 2a (of Fig. 2) is on a saturable core 7a thereby producing a saturable transformer. The core 7a does not operate in the fully saturated area; but, contrary, would under normal conditions operate in the nonlinear portion or knee

of the saturation curve. Such a nonlinear transformer 2a has certain advantages which makes it particularly useful in the disclosed circuit.

In the modification of Fig. 2, it is necessary that the capacitive reactance of capacitor 15 be sufficiently large with respect to the inductive reactance of the transformer 2a so that a leading current is drawn through the transformer primary 3 both during starting and while operating. When a leading current is drawn through the primary 3, a nonlinear transformer 2a will tend to keep the voltage across the lamps 16, 17 more nearly constant during voltage variations of the source 10, 11. Assume, for example, that the source voltage 10, 11 decreases so that a low voltage condition exists. The magnetizing reactance of the transformer 2a rises when the source voltage 10, 11 falls. As the reactance rises, the voltage across the nonlinear transformer 2a tends to increase due to the leading current through the transformer. As the voltage across the primary is additive to the line voltage, the voltage across the lamps 16, 17 will remain relatively constant. In other words, if the source voltage 10, 11 drops the increased voltage rise across the transformer 2a provides a counterbalancing effect giving good voltage regulation across the lamps. Now assuming the condition where the source voltage rises. In such instance, the reactance of the transformer 2a drops since the core 7a becomes more nearly saturated as the current tends to increase. This decreasing reactance of the transformer results in a voltage drop across the primary 3 of the transformer 2a even with a slightly greater current. Since a lower primary voltage is now added to the line voltage, the voltage across lamps 16 and 17 remains more nearly constant. Even though the source voltage is now greater, the rise across the transformer is smaller, and the lamp voltage remains relatively constant. For these reasons, it may be desirable, but not necessary, that the cathode heating transformer operate in the saturating area.

In accordance with the patent statutes, I have described what at present are considered to be the preferred embodiments of my invention. However, it will be obvious to those skilled in the art that various changes and modifications may be made in the disclosed structure without departing from the true spirit and scope of my invention, and it is, therefore, aimed in the appended claims to cover all such changes and modifications that fall within the true spirit and scope of my invention.

What is claimed as new and desired to secure by Letters Patent of the United States is:

1. Apparatus for operating at least one heated cathode discharge lamp from a source of alternating current of insufficient voltage to start and operate the lamp, comprising input means adapted to be connected to the source of supply current, a cathode heating transformer having a magnetic core, a primary winding on said core, means for connecting said lamp in series with said primary winding across said input means, cathode heating secondary windings on said core having leads for supplying cathode heating current to the cathodes of said lamp, and a capacitive reactor of greater capacitive reactance than the inductive reactance of said transformer at least during starting of said lamp and connected across said lamp in a series circuit with said primary winding across said input means, whereby leading current is drawn through said primary winding during starting of said lamp.

2. Apparatus according to claim 1 wherein said magnetic core operates in the nonlinear saturation area, and wherein said capacitive reactance is greater than the inductive reactance of said transformer during both starting and operating of said lamps whereby leading current is drawn through said primary winding during both starting and operation of said lamps.

3. Apparatus for operating at least two serially connected, heated cathode discharge lamps, from a source of alternating current of insufficient voltage to start and operate the lamps, comprising input means adapted to be

connected to the source of supply current, a cathode heating transformer having a magnetic core, a primary winding on said core, a current limiting reactor serially connected to said primary winding, means for connecting said serially connected lamps in a series circuit with said primary winding and said reactor across said input means, cathode heating secondary windings on said core having leads for supplying cathode heating current to the cathodes of the lamps, a starting capacitor having means for connection across one of said lamps to effect sequential starting thereof, and a capacitive reactor of greater capacitive reactance than the inductive reactance of said transformer at least during starting of said lamps and connected in a series circuit with said primary winding across said input means and in series circuit with said current limiting reactor across said lamps, whereby leading current is drawn through said primary winding during starting of said lamps.

4. Apparatus according to claim 3 above wherein said magnetic core operates in the nonlinear saturation area, and wherein said capacitive reactance is greater than the inductive reactance of said transformer during both starting and operating of said lamps whereby leading current is drawn through said primary winding during both starting and operation of said lamps.

5. Apparatus for operating a pair of serially connected, heated cathode discharge lamps from a source of alternating current supply voltage of insufficient voltage to start and operate the lamps, comprising a pair of input leads adapted to be connected to the source of supply current, a cathode heating transformer having a magnetic core, a primary winding on said core with one end connected to one of said input leads, a current limiting reactor having one end connected to the other end of the primary winding in series circuit therewith and having means for connecting its other end to the cathode of one

of said serially connected lamps, the second of said input leads having means for connection to the cathode at one end of the other serially connected lamp, a first cathode heating secondary winding on said core having leads for supplying cathode heating current to one of the cathodes of the first lamp, a second cathode heating secondary winding on said core having leads for supplying cathode heating current to the other cathode of said first lamp and one cathode of said second lamp, and a third cathode heating secondary winding on said core having leads for supplying cathode heating current to the other cathode in said second lamp, a capacitive reactor having one end connected to the connection between said transformer primary and said current limiting reactor and having the other end connected to said second input lead, the capacitive reactance of said capacitive reactor being greater than the inductive reactance of said primary winding at least during starting of said lamps whereby leading current is drawn through said primary winding during starting of said lamps, and a starting capacitor for connection across one of said lamps.

6. Apparatus according to claim 5 above wherein said core operates in the nonlinear saturation area, and wherein said capacitive reactance is greater than the inductive reactance of said transformer during both starting and operating of said lamps whereby leading current is drawn through said primary winding during both starting and operation of said lamps.
